US00D722607S

(12) **United States Design Patent**
van Os

(10) **Patent No.:** **US D722,607 S**
(45) **Date of Patent:** **** Feb. 17, 2015**

(54) **DISPLAY SCREEN OR PORTION THEREOF
WITH GRAPHICAL USER INTERFACE**

- (71) Applicant: **Apple Inc.**, Cupertino, CA (US)
(72) Inventor: **Marcel van Os**, San Francisco, CA (US)
(73) Assignee: **Apple Inc.**, Cupertino, CA (US)
(**) Term: **14 Years**
(21) Appl. No.: **29/449,297**
(22) Filed: **Mar. 14, 2013**

Related U.S. Application Data

- (63) Continuation of application No. 29/423,886, filed on Jun. 6, 2012, now Pat. No. Des. 712,421.
(51) **LOC (10) Cl.** **14-04**
(52) **U.S. Cl.** **D14/485**
(58) **Field of Classification Search**
CPC G06F 3/048; G06F 3/0481; G06F 3/0482
USPC D14/485-495
See application file for complete search history.

(57) **CLAIM**

The ornamental design for a display screen or a portion thereof with graphical user interface, as shown and described.

DESCRIPTION

FIG. 1 is a front view of a display screen or portion thereof with graphical user interface showing my new design; FIG. 2 is a front view of a display screen or portion thereof with graphical user interface showing my new design; FIG. 3 is a front view of a display screen or portion thereof with graphical user interface showing my new design; and, FIG. 4 is a front view of a display screen or portion thereof with graphical user interface showing my new design. The broken lines around the Figures showing a display screen or portion thereof form no part of the claimed design.

1 Claim, 1 Drawing Sheet
